US0D1091500S

(12) **United States Design Patent** (10) **Patent No.:** **US D1,091,500 S**
(45) **Date of Patent:** **** Sep. 2, 2025**

(54) **WIRELESS INTERCOM HEADSET**

(71) Applicant: **Shenzhen Xinlangrui Technology Co., Ltd.**, Shenzhen (CN)

(72) Inventor: **Enneng Gong**, Shenzhen (CN)

(**) Term: **15 Years**

(21) Appl. No.: **29/903,931**

(22) Filed: **Sep. 28, 2023**

(51) **LOC (15) Cl.** **14-01**

(52) **U.S. Cl.**

USPC **D14/205**; D14/223; D14/137

(58) **Field of Classification Search**

USPC D14/223, 137, 206, 226, 230, 217, 159, D14/205; D29/103; 2/209;

381/380-381, 386

Primary Examiner — Paula Allen Greene

(57) **CLAIM**

The ornamental design for a wireless intercom headset, as shown and described.

DESCRIPTION

FIG. 1 is a front view of wireless intercom headset;

FIG. 2 is back view thereof;

FIG. 3 is a left view thereof;

FIG. 4 is a right side view thereof;

FIG. 5 is a bottom view thereof;

FIG. 6 is a top view thereof;

FIG. 7 is a perspective view thereof; and,

FIG. 8 is another perspective view thereof.

The broken lines depict portions of the wireless intercom headset that forms no part of the claimed design.

1 Claim, 8 Drawing Sheets
